UNITED STATES PATENT OFFICE.

ELIOT O'HARA, OF WALTHAM, MASSACHUSETTS.

LUMINOUS SWITCH-INDICATOR.

1,296,311.

Specification of Letters Patent.

Patented Mar. 4, 1919.

Application filed September 20, 1918. Serial No. 254,981.

To all whom it may concern:

Be it known that I, ELIOT O'HARA, a citizen of the United States, residing at Waltham, county of Middlesex, State of Massachusetts, have invented a certain new and useful Improvement in Luminous Switch-Indicators, of which the following is a specification, reference being had therein to the accompanying drawings.

10 The object of the invention is to provide a separable device which may be readily attached to a switch plate to serve as an indicator or finder in the dark for the switch or a push button. The invention consists in 15 making a device of the character described in a form which may be sold as a separate article of manufacture and may be readily attached to one of the ordinary switch plates and yet which presents enough difficulty in 20 removal to prevent easy theft.

The invention will be fully understood from the following description when taken in connection with the accompanying drawings and the novel features thereof will be 25 pointed out and clearly defined in the claims at the close of this specification.

In the drawings, Figure 1 is a view showing in elevation a switch plate attached to a wall and having a device embodying the invention attached thereto.

Fig. 2 is a perspective view of the device embodying the invention detached.

Fig. 3 is a vertical sectional view of the device shown in Fig. 2.

Fig. 4 is a section on line 4—4 of Fig. 3.

Fig. 5 shows a modified form of means for attaching the device to the switch plate.

Referring now to the drawings, 1 represents an ordinary switch plate attached to a 10 wall and having the two push buttons 2, 3, one of which is pushed in to turn on the light and the other of which is pushed in to turn off the light. The switch plate is ordinarily secured to the wall by screws 4, 5.

15 The device embodying the invention has a main body portion 6 which is to lie on the front face of the switch plate and a hooked portion 7 which may be made to engage over one edge of the switch plate 1. The preferred place of engagement is at the upper 0 end of the switch plate as shown in the drawings. Preferably this hooked portion is an extension of the body 6. The body portion 6 of the device is formed with a hole 8 so located that when the device is slipped

onto the switch plate as shown in Fig. 1, the said hole 8 will be in alinement with the screw hole in the switch plate provided for the screw 4, so that the screw 4 may be used not only for fastening the switch plate 1 to the wall of the room or other supporting surface, but also for securing the indicator device to the switch plate.

60 The device is provided with a luminous pointer of some kind in the body portion 6, 65 said indicator being of such form and so disposed on the body portion 6 that when the device is attached to the switch plate, the pointer will point in the direction of the push button. The preferred form and 70 method of constructing the indicator is as follows: The body portion 6 is preferably of metal and the preferred metal is brass, although this is not essential. A slot 9 is cut through the metal of a design suitable for an 75 indicator. The preferred form of design is in the shape of an arrow with the pointed end of the arrow pointing toward the push buttons 2, 3 when the device is attached to the switch plate as shown in Fig. 1. Any 80 other suitable form of pointer however may be employed.

Applied to the back face of the body portion 6 of the device is a sheet of material 10 which has applied to one face thereof luminous material 11, which renders the sheet 10 luminous in the dark. This sheet 10 is preferably made of some transparent material such for instance as celluloid, glass, mica or gelatin having a coating 11 of some suitable 90 luminous substance, preferably a self luminous material containing radium. There is thus exposed through the arrow shaped aperture 9 a portion of the sheet 10 which in the dark appears as a luminous arrow. The 95 coating is preferably on the back side of the sheet 10 so that it will be protected from the wear which would come to it through the slot 9 if it were on the front face. The celluloid being some transparent or at least 100 translucent allows the front face to be rendered luminous even though the coating is on the back face.

105 Preferably the sheet 10 has an embossed portion in form of an arrow of a size and shape to fit into the arrow shaped opening 9 in the body plate 6.

The sheet 10 may be secured to the back face of the body plate 6 in any suitable manner to retain it in proper position. The pre- 110

ferred method of securing it in place is by crimping over the edges of the body plate 6, forming a lip or flange 12 which engages over the edges of the sheet 10 as shown in Fig. 4. In order to protect the luminous substance 11 there is preferably provided a backing 13 of some suitable sheet material as for instance an opaque celluloid sheet so as to keep the luminous material from contact with the switch plate.

In such case the flange 12 will engage the back side of the backing 13 instead of coming directly in contact with the sheet 10.

In the modification shown in Fig. 5 the body plate 6 is formed with a plurality of tabs 14 instead of a continuous flange 12 to clamp the luminous plate to the back of the body plate 6.

While the form of pointer is shown as in the shape of an arrow it may of course be of any other suitable form. Also instead of having the sheet 10 attached to the back face of the body member 6 and showing through a slot, the luminous pointer may be attached to the front face of the body member 6 or even be painted directly on the front face of the metal body 6 by means of luminous paint. The main feature of the invention is a separable device made as a separate article of manufacture and provided with a luminous indicator forming a part of the body of the device, the device being so constructed and arranged that it may be readily attached to an ordinary switch plate so that when so attached the indicator will point toward the switch button or buttons.

The device may be attached to the switch plate without removing the switch plate from the wall. This is done by simply removing the upper screw 4 to permit the upper end of the switch plate to be slightly lifted away from the wall, enough to make a slight crevice so that the hook 7 may be engaged over the top of the switch plate in the position shown in the drawings and then the screw 4 will be set up again thus clamping the switch plate firmly to the wall and clamping the leg of the hook portion 7 of the indicator device firmly between the switch plate and the wall.

The device is thus secured so that it cannot be snatched off quickly by a thief as could be done if it were simply hooked onto the switch plate, yet it is capable of removal if occasion requires, without damage to the switch plate.

What I claim is:

1. A switch plate indicator attachment comprising a body plate having a slot therein shaped in the form of a pointer, said slot extending through the body plate, a luminous sheet secured to the back face of the body plate covering said opening in such manner that a luminous design is shown

through the said slot corresponding with the contour of the slot, means for securing said luminous sheet to the body plate, and means for securing the said device to a switch plate.

2. A switch plate indicator attachment comprising a body plate having a slot therein shaped in the form of a pointer, said slot extending through the body plate, a luminous sheet secured to the back face of the body plate covering said opening in such manner that a luminous design is shown through the said slot corresponding with the contour of the slot, and means for securing said luminous sheet to the body plate, said body plate being formed with a hooked extension at one end to engage over one end of a switch plate and being formed with a screw hole whereby a single screw may pass through the indicator attachment and through a switch plate into a support.

3. As an independent article of manufacture, an indicator comprising a body member having thereon a pointer which is self-luminous in the dark and which is of such design that it points plainly in a definite direction, said body member having a hook portion which is adapted to engage in such position over one edge of a support which contains the object to be pointed out that the said pointer will indicate definitely the exact line of direction to the said object.

4. A switch plate indicator attachment comprising a body plate portion having a slot therein shaped in the form of a pointer, said slot extending through the said body plate, a luminous sheet applied to the back face of the body plate covering said opening and exposing through said opening a luminous design corresponding in contour with the contour of the slot, a sheet of opaque material applied to the back face of said luminous sheet, and means for securing said backing and said luminous sheet to the back face of the body plate.

5. A switch plate indicator attachment comprising a body plate portion having a slot therein shaped in the form of a pointer, said slot extending through the said body plate, a luminous sheet applied to the back face of the body plate covering said opening and exposing through said opening a luminous design corresponding in contour with the contour of the slot, said body plate being formed with flanges which clamp the luminous sheet to the back face of said body plate, said body plate also being formed with a hooked extension which is adapted to engage over one edge of a switch plate and is formed with a screw hole to receive a screw to pass through the said body plate and through a switch plate into a supporting surface.

6. A switch plate indicator attachment comprising a body portion having thereon a pointer which is luminous in the dark, said body having a hooked portion to en-

gage over one edge of a switch plate and thereby permit the body portion to overhang the front face of the switch plate.

7. A switch plate indicator attachment 5 comprising a body portion having thereon a pointer which is luminous in the dark, said body having a hooked portion to engage over one edge of a switch plate and thereby permit the body portion to overhang the front 10 face of the switch plate, said body plate being formed with a screw hole to receive a screw to pass through the body plate and switch plate.

8. A switch plate indicator attachment comprising a body plate portion having a 15 slot extending therethrough, a sheet of material secured to the back of said body plate covering said opening, said sheet having on that portion which is exposed through the slot a material which is luminous in the dark, 20 and a hook for securing said body plate to a switch plate in such manner as to overlie the front face of the switch plate.

In testimony whereof I affix my signature.

ELIOT O'HARA.
